*E. A. Stevens,
Ship Building*

No. 36.860.

Patented Nov. 4, 1862.

UNITED STATES PATENT OFFICE.

EDWIN A. STEVENS, OF HOBOKEN, NEW JERSEY.

IMPROVED MEANS OF PROTECTING WAR-VESSELS.

Specification forming part of Letters Patent No. **36,868**, dated November 4, 1862.

To all whom it may concern:

Be it known that I, EDWIN A. STEVENS, of Hoboken, in the county of Hudson and State of New Jersey, have invented a new and useful Method of Protecting War-Vessels from Injurious Effects from an Enemy's Shot; and I do hereby declare that the following is a full and exact description of the same, reference being had to the accompanying drawing, making part of this specification, and being a transverse section of a vessel illustrating my said invention.

I have by experiment discovered that the substance of a sheet of india-rubber fastened to the side of a structure of wood or other ship-building material will not be detached from such sheet in any material degree by the effect of a shot that passes through said structure and through the rubber, but that the rubber will split and expand, so as to let the shot through, and then return nearly to its original shape and nearly or quite close the orifice. This effect is most complete when the rubber is placed inside of said structure.

In this case another important effect of the rubber is to prevent the flying of the splinters of the wood or other material. I therefore employ an inner or an outer sheathing of rubber, or both, on the sides of the vessel, for the purposes described; and my invention particularly consists in the use of such a sheathing of india-rubber upon the sides, top, or bottom of chambers or vessels containing water employed as a protection against missiles.

To enable others skilled in the art to fully understand and use my invention, I will proceed to describe the same with reference to the drawing.

A A represent the sides of the vessel.

B is a water-tight deck which may be covered with a body of water to protect the deck from injury by an enemy's shot.

C is an upper deck covering and confining the water upon the deck B.

D D are partitions by which the water-space

between the decks B and C is divided into a number of compartments or tanks.

E E represent a sheathing of india-rubber, which may be applied to the sides A and deck B, on either the external or internal surface, or both, in any part which can possibly be pierced by an enemy's shot. The effect of the said sheathing will be to close the aperture made by a shot, as hereinbefore explained, so as to prevent any considerable flow of water through it. The vessel may thus be preserved from sinking, if the aperture made by the shot be below the water-level, or in the event of a shot penetrating the wall of a water-chamber located above the sea-level and employed to submerge the vessel for purposes of defense, the escape of the water within the said chamber and the consequent rising of the vessel will be prevented. In like manner the application of the gum sheathing to the water-deck B will close the aperture therein, if from an insufficient depth of water or other cause a shot should by any possibility penetrate the said deck. The water upon the deck will thus be prevented from flowing into the interior of the vessel, and will remain to protect the deck from further injury.

I am aware that it has before been proposed to use a sheathing of india-rubber to automatically close an aperture made by a projectile.

Having thus described my invention, what I claim therein as new, and desire to secure by Letters Patent, is—

The use of a sheathing of gum elastic or equivalent material applied internally or externally to the side, top, or bottom of a chamber or vessel containing water to be used for immersing ships, or as a protection against projectiles.

E. A. STEVENS.
